DESIGN.

No. 32,456.

Patented Apr. 3, 1900.

W. E. KIRCHHOFF.
WASHBOARD.

(Application filed Mar. 9, 1900.)

UNITED STATES PATENT OFFICE.

WILLIAM E. KIRCHHOFF, OF SCRANTON, PENNSYLVANIA.

DESIGN FOR A WASHBOARD.

SPECIFICATION forming part of Design No. 32,456, dated April 3, 1900.

Application filed March 9, 1900. Serial No. 8,085. Term of patent 7 years.

To all whom it may concern:

Be it known that I, WILLIAM E. KIRCHHOFF, a citizen of the United States, residing at Scranton, in the county of Lackawanna and State of Pennsylvania, have invented and produced a new and original Design for Washboards, of which the following is a specification, reference being had to the accompanying drawings, forming part thereof.

In the accompanying drawings, in which like reference characters denote like parts in the several views, Figure 1 is a plan view of a washboard embodying my new and original design; Fig. 2, a partial section thereof upon the line 2 2 of Fig. 1, and Fig. 3 a partial section thereof upon the line 3 3 in Fig. 1.

As shown in the drawings, the leading or material feature of my design comprises a plurality of compositely-arranged diamond-shaped sections of two separate and distinct forms, denoted, respectively, by the general reference characters 4 and 5. The diamond-shaped sections 4 each embody a plurality of parallel surface ridges 4^a, arranged in parallelism with one of the sides of the respective section and each having a broad face or side 4^b and a relatively-narrow face or side 4^c. The corresponding ends of the ridges 4^a are cut off or beveled at 4^e at an angle with the surface plane of the washboard corresponding with the similar angle formed by each of the relatively-narrow faces or sides 4^c thereof, and the opposite ends of the ridges 4^a are cut off or beveled at 4^e at an angle with the surface plane of the washboard corresponding with the similar angle formed by each of the broad faces or sides 4^b thereof.

The diamond-shaped sections 5 each embody a plurality of surface ridges 5^a, 5^b, and 5^c, arranged in parallelism with the longer axis of the respective section 5. The ridge 5^a embodies two narrow angularly-divergent faces 5^d and one relatively-broad face 5^e. The ridge 5^b embodies a narrow face 5^f and a relatively-broad face 5^g, the ends 5^h of the ridges 5^b being cut off or beveled at an angle with the surface plane of the washboard coincident with the similar angle formed by the narrow face 5^f thereof. The ridge 5^c embodies a top face 5ⁱ, approximately parallel with the surface plane of the washboard, a narrow face or side 5^j, and two relatively-broad faces or sides 5^m, which form each an angle with the surface plane of the washboard approximately equal to the similar angle formed by the face or side 5^g of the ridge 5^b. The several edge sections 4 and 5 are cut away to form a regularity of composite edge formation.

Having fully described my invention, I claim as new and desire to secure by Letters Patent—

The design for a washboard, substantially as herein shown and described.

In testimony that I claim the foregoing as my invention I have signed my name, in presence of the subscribing witnesses, this 7th day of March, 1900.

WILLIAM E. KIRCHHOFF.

Witnesses:

JOHN LENTES,
F. W. KIRCHHOFF.
